Primary Examiner — Barbara Fox(74) *Attorney, Agent, or Firm* — Maschoff Brennan(57) **CLAIM**

The ornamental design for an electronic device, as shown and described in the Figures.

DESCRIPTION

FIG. 1 is a perspective view of an electronic device showing the new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof; and,

FIG. 7 is a rear elevational view thereof.

The broken lines in FIG. 6 indicate environmental structure only that forms no part of the claimed design.
